UNITED STATES PATENT OFFICE.

ERNEST THEODORE OFELDT, OF SPRING LAKE, NEW JERSEY, ASSIGNR OF ONE-HALF TO ROBERT A. CHESEBROUGH, OF SPRING LAKE, NEW JERSEY.

AUTOMATIC GAS-CONTROLLER.

1,346,051.

Specification of Letters Patent.

Patented July 6, 1920.

Application filed September 30, 1919. Serial No. 327,548.

To all whom it may concern:

Be it known that I, ERNEST T. OFELDT, a citizen of the United States, and a resident of Spring Lake, in the county of Monmouth and State of New Jersey, have invented a new and Improved Automatic Gas-Controller, of which the following is a full, clear, and exact description.

This invention relates to improvements in automatic gas controllers, and more particularly to automatic means for controlling the feed of gasoline and air to an internal combustion engine in accordance with the speed of the engine.

15 A further object is to provide improvements of the character stated, which result in an economy of fuel and a more perfect running engine.

20 A further object is to provide improvements of the character stated, which can be attached to any gasoline engine and which operate as an adjunct to manually control the means so that the desired proportion of gasoline and air can be manually 25 regulated for starting and then automatically regulated after the engine is warmed up.

With these and other objects in view the invention consists in certain novel features 30 of construction, and combinations and arrangements of parts, as will be more fully hereinafter described and pointed out in the claims.

In the accompanying drawings—

35 Figure 1 is a view in section illustrating my improvements; and

Fig. 2 is a fragmentary plan view.

A represents a carbureter having a float chamber 1 and a mixing chamber 2, the latter in the form of an elbow pipe, as shown. A float 3 is provided in chamber 1 and is fixed to a needle valve 4 controlling the intake of gasoline from an inlet 5 and a pipe 6 connects the chamber 1 with a nozzle 7 longitudinally disposed in the mixing chamber 2. A needle valve 8 controls the outlet from the nozzle 7, and dampers 9 and 10 are provided in the ends of the mixing chamber. Rotary shutters 11 and 12 control the admission of air to the mixing chamber and a rod 13 is connected to one of these shutters and is adapted to be manually operated in any approved manner.

The stem 14 of the needle valve 8 is screw threaded, as shown at 15, and engages the

internal threads of a sleeve which is on the mixing chamber so that when the stem 14 is turned, it will cause the valve to move toward or away from the nozzle 7 and regulate the escape of gasoline into the mixing 60 chamber.

A crank arm 17 is secured to the end of stem 14 and a sliding rod 18 is operatively connected to the crank arm 17 so that the longitudinal movement of the rod 18 causes 65 a turning movement of the stem 14 to operate the needle valve 8. A lever 19 having a manually controlled rod 20 connected thereto engages one of the collars 30 on the rod 18 to permit the manual movement of 70 the rod 18 and the valve 8 through the medium of any desired mechanism, as will be understood.

21 represents a governor casing in which a shaft 22 has rotary mounting and a pulley 75 23 on one end of the shaft 22 is adapted to be driven from any suitable part of the engine, not shown. In fact, any desired power transmission means may be employed between the shaft 22 and the engine so that 80 the shaft is turned as the engine is driven. Weighted arms 24 are carried by the shaft 22 and are adapted to be bowed by centrifugal force to move a grooved collar 25 longitudinally of the shaft 22. A lever 26 projects into the casing 21 and is pivotally supported on a bracket 27. One end of this lever 26 engages the grooved collar 25 so that the movement of the collar causes a 85 pivotal movement of the lever. 90

The lever 26 near its opposite end is connected to a sliding sleeve 28 on the rod 18 and compensating springs 29 are positioned around the rod 18 at opposite sides of the sleeve 28 and bear against collars 30 fixed 95 to the rod 18. The extreme end of the lever 26 is connected to a rod 31 and the latter to the shutter 12.

The operation is as follows: As above stated, the needle valve 8 can be manually 100 controlled by means of the rod 20 and the shutter 11 can be manually controlled by means of the rod 13 to allow any desired mixture to be supplied to the engine to start it. After the engine is warmed up and 105 is running at a predetermined speed, the weighted arms 24 are thrown outwardly by centrifugal force, and through the medium of the collar 25 and lever 26, rods 18 and 31 are moved longitudinally. The rod 18 by 110

reason of its engagement with the crank arm 17 causes a rotary movement of the stem 14 to move the needle valve 8 toward the nozzle 7 and reduce the flow of gasoline, 5 while the rod 31 operates the shutter 12 to increase the supply of air.

The chambers 9 and 10 are positioned as desired to suit conditions and hence while the engine is running the supply of gasoline 10 and air is automatically controlled in accordance with the speed. This results in an economy of fuel and in a more perfect combustion and relieves the operator of the necessity for manually controlling the mixture in 15 accordance with the speed.

Various slight changes may be made in the general form and arrangement of parts described without departing from the invention, and hence I do not limit myself to the 20 precise details set forth but consider myself at liberty to make such changes and alterations as fairly fall within the spirit and scope of the appended claims.

I claim:

25 1. The combination with a carbureter, of a gasoline feed valve, an air valve, a pair of air intake shutters for said air valve, automatic means for controlling the position of the gasoline feed valve and the movement of 30 one of the shutters by the speed of the engine, and manually operated means for moving the gasoline feed valve and moving the other of said shutters.

2. The combination with a carbureter, a 35 rotary needle valve controlling the outlet of gasoline from the carbureter, a shutter controlling the intake of air, a governor adapted to be operatively connected to an engine, a lever moved by the governor, a crank arm 40 on the needle valve, a rod connecting the crank arm and lever, a rod connected to the shutter and to said lever, a sleeve mounted to slide on the first-mentioned rod and connected to the lever, fixed collars on the 45 first-mentioned rod, and coiled springs on the

sleeve-carrying rod between the sleeve and the collars.

3. The combination with a carbureter, a rotary needle valve controlling the outlet of gasoline from the carbureter, a shutter controlling the intake of air, a governor adapted to be operatively connected to an engine, a lever moved by the governor, a crank arm on the needle valve, a rod connected to the crank arm, means connecting the shutter and lever, a sleeve mounted to slide on the rod and connected to the lever, fixed collars on the rod, coiled springs on the rod between the sleeve and the collars, and manually operated means for moving the rod. 50

4. The combination with a carbureter, a rotary needle valve controlling the outlet of gasoline from the carbureter, a shutter controlling the intake of air, a governor adapted to be operatively connected to an engine, a lever moved by the governor, a crank arm on the needle valve, a rod connected to the crank arm, means connecting the shutter and lever, a sleeve mounted to slide on the rod and connected to the lever, fixed collars 60 on the rod, coiled springs on the rod between the sleeve and the collars, a second shutter controlling the inlet of air, manually operated means engaging said shutter, and manually operated means for moving the needle valve. 65

5. A device of the character stated, comprising a mixing chamber, a gasoline supply means, a nozzle in the mixing chamber communicating with said means, a rotary screw 80 threaded needle valve controlling the outlet from the nozzle, a pair of shutters controlling the inlet of air to the mixing chamber, a governor operatively connected to the needle valve and to one of the shutters, a manually controlled means for moving the needle valve, and a second manually controlled means for moving one of the said shutters. 85

ERNEST THEODORE OFELDT.
